UNITED STATES PATENT OFFICE.

ALBERT J. BATES, OF CHICAGO, ILLINOIS.

METAL STRUCTURE.

1,010,408.

Specification of Letters Patent. Patented Dec. 5, 1911.

Application filed July 17, 1909. Serial No. 508,199.

To all whom it may concern:

Be it known that I, ALBERT J. BATES, of Chicago, Cook county, Illinois, have invented a new and useful Improvement in Metal Structures, of which the following is a full, clear, and exact description, reference being had to the accompanying drawings, forming part of this specification, in which—

Figure 1 is a perspective view of a post or pole structure embodying my invention; Figs. 2 and 3 are detail views of portions of the structure; Fig. 4 is an elevation showing a modified form of structure; Fig. 5 is a section on the line V—V of Fig. 4; and Figs. 6 and 7 are perspective views showing portions of two other forms of structures.

My invention has relation to metal structures capable of use for fence posts, telegraph, telephone, electric light and other poles; also as a reinforcement for concrete and for various other purposes.

The object of my invention is to produce a structure of this character having great strength and rigidity in proportion to the weight of the material used, so that efficiency can be obtained at a cost not exceeding the cost of wood, and consequently, the metal structure can be used as a substitute for wood.

The nature of my invention will be best understood by reference to the accompanying drawings, in which I have shown a number of different embodiments thereof, and which will now be described, it being pre-
25 wised, however, that the forms shown are illustrative only of my invention, and that it is capable of various other embodiments within the spirit and scope of the appended claims.

40 In the form of the invention shown in Figs. 1, 2, and 3, which illustrate my invention as applied to the construction of a fence post, the post is in the form of a frame which is triangular in cross section and has the three parallel longitudinal metal rods 2, 3 and 4. These parallel rods are bound together, so as to form panels by means of truss rods, which extend in zig-zag fashion back and forth between each adjacent pair 45 of parallel rods. These diagonal or zig-zag truss rods are preferably continuous from end to end, although this complete continuity is not essential to my invention, broadly considered. Each truss rod 5 at the apices 50 of the angles, is bent into the form of a double loop 6, of the shape shown in the drawing, and the rods 2, 3, and 4 are passed through the respective loops thus formed.

55 In the preparation of the post, the truss rods are previously prepared by being bent in zig-zag form and provided with loops at the apices, as above described, and the parallel rods are threaded through the eyes of the loops.

60 In the construction shown in Figs. 1, 2, 65 and 3 of the drawings, there are three panels, each made up of a single zig-zag truss rod, prepared as above described; and in assembling the several panels, each parallel rod passes through the eyes of two sets of loops 70 of the truss rods, and the eyes or loops of these respective rods alternate with one another, as shown at the eyes 6, 6'. When the parts have been thus assembled, in the manufacture of the post, a strong outward pull is 75 exerted in a direction at right angles to their length, the pull being applied at the eyes of the truss rods. The effect of this is to form in the parallel rods at the eyes of the truss rods short kinks or bends 7, and also to 80 stretch the metal of the truss rods somewhat, so as to straighten them and set the loops tightly on the longitudinal rods. The stretching is carried somewhat beyond the elastic limit of the truss rods, so that they 85 are made very rigid and are bound firmly upon the parallel rods and can not be displaced. The whole structure thus becomes a rigid and practically unitary device. In the form described in these figures, the post is 90 triangular in cross section and each of the panels formed by the truss rods is composed of triangular sections, thereby making a structure which is not only triangular in its general outline, but which is composed wholly 95 of triangularly arranged elements. The truss effect thus produced, contributes greatly to the rigidity of the structure, since all these elements are subjected only to tension and compression strains, and the structure, therefore, possesses great resistance to 100 any change in its form, the principle involved being the use of triangles, which, as is well known, can not change their shape without a change in the length of one of 105 their members. The act of stretching the truss rods beyond their elastic limit puts a set in them which leaves them perfectly straight, and the form given the loop-knots, by which they are engaged with and secured 110 to the longitudinal rods, is such, as will be seen from the drawings, (Fig. 1) that the

axes of the truss rods intersect the axes of the longitudinal rods. By reason of this construction, it will be readily seen that the strains are in direct lines without any tendency to distort the structure.

When the structure is employed as a fence post, telegraph pole, or other structure which is to be set in the ground, it is desirable in some cases to provide it with a concrete or other plastic base, such, for instance, as is shown at B in Fig. 1. This base is shown in Fig. 1 as consisting of a hollow triangular shell in which the diagonal truss rods are embedded. The provision of this shell does not add greatly to the weight of the structure, while it increases very largely the surface area of the buried portion of the structure, which is effective as a resistance bearing for the soil. It also protects the metal of the post from corrosion. This may, however, be dispensed with, if desired, and instead of extending the shell entirely to the lower end of the structure, as shown in Fig. 1, it may, as shown at B' in Fig. 7, surround only a part of the buried portion of the structure.

In Fig. 4, I have shown another form of my invention in which only two parallel longitudinal rods 9 and 10 are employed, these two rods being connected by a truss rod 11, which is arranged and is connected to the longitudinal rods in the same manner as the truss rods 5, shown in Figs. 1, 2 and 3. This form of my invention is well adapted for use as a metal reinforcement for concrete constructions. It also may be used as a fence post, the rods employed being heavier, if necessary, than those used in the construction shown in Figs. 1, 2 and 3.

40 In the form of my invention which is illustrated in Fig. 7, four of the parallel longitudinal rods 12 are employed, being connected by truss rods 13 of the same character and arrangement as in the other figures. The structure thus formed is a hollow rectangular structure, composed of four panels, the looped knots connecting the truss rods with the longitudinal rods being in staggered relation to form triangles, as 50 shown.

In the form shown in Fig. 6, four longitudinal rods 14 are employed, as in Fig. 7, but the truss rods 15 are omitted at one side of the structure, this side being left open.

55 It will be readily understood that structures embodying the basic features of my invention can be made having more than four longitudinal rods, each adjacent pair of such rods being connected by truss rods 60 in the manner described.

The advantages of my invention are many

and will be appreciated by those skilled in the art.

The structures can be manufactured at a comparatively low cost, it being possible to use rolling mill products entirely.

The structures can be made of various sizes and lengths, according to the purpose for which it is desired to use them, and their weight is exceedingly low in proportion to their strength and rigidity. The construction is also such as to offer but little resistance to wind pressures.

I claim:

1. A metal structure composed of longitudinal rods and zigzag truss rods, each truss rod being bent into a loop knot at each apex, and adjacent longitudinal rods passing through the corresponding loops of each truss rod, substantially as described.

2. A metal structure having longitudinal rods and diagonal looped truss rods, adjacent longitudinal rods extending through the corresponding loops of the same truss rod, the latter being stretched beyond their elastic limit, and the longitudinal rods being crimped at the loops, substantially as described.

3. A metal structure triangular in cross section having three parallel corner rods, and three truss rods, each truss rod extending in zigzag form between and looped around adjacent longitudinal rods, thereby forming a series of triangles, each truss rod being bent at each apex into a loop knot, and each corner rod passing through corresponding looped knots, substantially as described.

4. A metal structure composed of longitudinal rods connected by continuous truss rods, each truss rod being of zig-zag form and united to adjacent longitudinal rods by loop-knots at their apices.

5. A metal structure composed of longitudinal members connected by truss rods zig-zag in form, each truss rod having loop-knots at the apices of its angles through which adjacent longitudinal rods pass, and said truss rods having a permanent set.

6. A metal structure composed of longitudinal members connected by truss rods zig-zag in form, each truss rod having loop-knots at the apices of its angles through which adjacent longitudinal rods pass, and said truss rods having a permanent set, the longitudinal rods also having a permanent set.

In testimony whereof, I have hereunto set my hand.

ALBERT J. BATES.
